W. S. PELOUBET

CATAMENIAL SACK AND WOMB SUPPORT

Filed Feb. 16, 1925

William S. Peloubet INVENTOR

BY
Thomas Howe ATTORNEY

UNITED STATES PATENT OFFICE.

WILLIAM S. PELOUBET, OF NEW YORK, N. Y.

CATAMENIAL SACK AND WOMB SUPPORT.

Application filed February 16, 1925. Serial No. 9,398.

This invention relates to devices adapted to receive and retain excretions of the female organs at the mouth of the womb and also to act as a support in cases of weakness or 5 displacement of the womb.

The main object of the invention is to provide a device of the character as indicated which shall be readily handled, simple in construction and such as may be made use of 10 without injury.

Other and ancillary objects of the invention will appear hereinafter.

In the accompanying drawings, which illustrate the invention,

15 Fig. 1 is an axial section of a device embodying the invention,

Fig. 2 is a top plan view of the same,

Fig. 3 is a side elevation, partly broken away to show a section, of a modified form 20 of the device,

Fig. 4 is a top plan view of the device shown in Fig. 3, showing the cup partially expanded, and

Fig. 5 is a similar view of the cup of 25 Figs. 3 and 4 showing the cup in contracted position.

Referring to the drawings, and first to Figs. 1 and 2, the article therein shown is formed of molded rubber of suitable flexibility, elasticity and stability, and comprises 30 a cup 1 in communication, by means of an opening 2 with a disk-shaped pocket or receptacle 3 having substantially flat sides and extending laterally to a considerable distance 35 outside the extreme lateral edges of the cup.

To the other flat side of the receptacle is secured a similar cup 4.

The two cups and pocket are in axial alignment.

40 The device is to be inserted in the vaginal passage with the disk-like pocket transverse thereto. The cup 1 receives the end of the womb so that the menstrual discharge is directed into the pocket 3. The flat pocket, extending a considerable distance outside the cups, engages with the walls of the vaginal passage in a substantially fluid tight manner so that the cup 1 is centered and any excretion which may be outside the cup is caught.

The centering of the cup adjusts into proper 50 position the end of the uterus if it has become displaced to one side, and a support for the womb is formed which is especially efficacious in cases of "falling of the womb". This support may be afforded by engagement 55 of the disk pocket with the vaginal walls. The cup 4 provides additional pelvic support and also, with or without such support, prevents displacement of the device by undue tilting of the disk and cup 1 with 60 relation to the vaginal walls.

To render either or both of the cups more flexible, so as to be expanded and contracted to adjust the device to the parts as required by the circumstances of the individual case, 65 with greater ease, there may be formed in the cup radial sections 5 of less thickness than the remainder of the wall of the cup, these sections puckering to form a pleat when the cup is in contracted condition (see 70 Figs. 3 and 5), and this pleat spreading on enlargement or expansion of the mouth of the cup (see Fig. 4).

While the invention has been illustrated in what are considered its best applications, 75 it may have other embodiments without departing from its spirit and is not therefore limited to the structures shown in the drawings.

What I claim is:

1. A device of the character described having two cups and a disk-like pocket in axial alignment, one of said cups being in communication with the interior of said pocket and the other being shut off from 85 communication therewith.

2. A device of the character described of molded rubber having a disk-like pocket and a cup on each side thereof in substantially axial alignment, one of said cups communicating with the interior of said pocket and the other cup being shut off from such communication, said pocket extending laterally beyond the extreme lateral edges of said cups.

95 In testimony whereof I have signed this specification this 14th day of February 1925.

WILLIAM S. PELOUBET.
